UNITED STATES PATENT OFFICE.

WILLIAM H. GALE, OF PROVIDENCE, RHODE ISLAND.

STAMP-AFFIXING MACHINE.

1,285,113.

Specification of Letters Patent. Patented Nov. 19, 1918.

Application filed December 10, 1914. Serial No. 876,424.

To all whom it may concern:

Be it known that I, WILLIAM H. GALE, a citizen of the United States, and resident of the city of Providence, in the county of 5 Providence and State of Rhode Island, have invented certain new and useful Improvements in Stamp-Affixing Machines, of which the following is a specification.

The invention relates to stamp affixing 10 machines and has for its object to provide such a machine of a small size and which is of simple and practical construction the same having a stamp affixing plunger and feed rolls for advancing a strip of stamps 15 to be severed at predetermined intervals and automatically affixing a stamp to an envelop or other mail matter all by the operation of the plunger.

A further object of the invention is to 20 provide means whereby the feed rolls are positively operated by the action of the plunger to feed the strip the length of one stamp at a time and to positively limit each feeding movement of said rolls and so prevent 25 an overfeeding of the stamp strip where the plunger is forced down rapidly.

A further object of the invention is to provide means whereby the rolls may be operated independent of the action of the 30 plunger for the purpose of adjusting the stamp strip relative to the cutters.

The invention further consists in the provision of means whereby the feeding rolls cannot be operated to feed the stamp strip 35 without operating the counter thereby rendering it impossible for any person to surreptitiously remove stamps without causing the same to be registered.

With these and other objects in view, the 40 invention consists of certain novel features of construction, as will be more fully described, and particularly pointed out in the appended claims.

In the accompanying drawings:

45 Figure 1—is a plan view of my improved machine with the casing partly broken away to better illustrate the internal mechanism.

Fig. 2—is a central sectional side elevation showing the stamp roll located in the base beneath the plunger and the stamp strip leading therefrom through the feed rolls to the cutter.

50 Fig. 3—is a front elevation of my improved machine with the casing partially broken away to show the interior thereof.

Fig. 4—is a side elevation with the casing in section illustrating the means by which the feeding rolls are caused to operate, the counter also showing one of the springs for 60 returning the plunger to normal.

Fig. 5—is a perspective view showing the general construction of the plunger with its two spaced apart guide bars and the rack and pinion mechanism through which the 65 feeding rolls are operated by the action of said plunger.

Fig. 6—is a side elevation slightly enlarged showing the rack and the mutilated gear through which the feed rolls are operated. 70

Fig. 7—is a front elevation showing the feed rolls, one being pressed downward by a spring and the other partly in section showing it as provided with frictional 75 means whereby said rolls may be rotated independent of the action of the plunger for the purpose of setting the strip relative to the cutters.

Fig. 8—is a front elevation of the movable cutter blade. 80

Fig. 9—shows the rack at the end of its downward stroke and its plane edge serving as a positive stop against further rotation of the pinion. 85

Referring now to the drawings 10 designates the base portion of the outer casing 11, which casing may be made of any suitable material, but I preferably construct the same of a molded vulcanized fibrous material of a special character by the use of which I obtain several manufacturing advantages. The back plate 12 of this casing is adapted to be readily removed and by this means I am enabled to insert a skeleton 90 frame portion 13 of stamped sheet stock in which the various parts of the mechanism are operatively mounted. In the lower portion of this skeleton frame I have provided longitudinal slots 14 into which the arbor 15 of the stamp roll 16 may be passed and rotatably mounted to locate the roll in the base portions below the plunger where it occupies what in other machines of this character is waste space. I have also provided on either side of this frame two pins 17 which serve as guides extending into slots 17^a in the spaced apart guide bars 18 extending downward from the head or flange 19 which together form the plunger. 100

By my improved construction of providing two guide bars for the plunger, I am ena-

bled to form a strong well guided structure and one of said bars is arranged to carry a plurality of teeth 20 thereby producing a short section of rack for the purpose of engaging and operating the feed rolls in the manner presently described.

These feed rolls 21 and 22 are preferably formed of a diameter whose circumference is exactly the length of one of the stamps 10 and are driven in time with each other through the gears 23 and 24. The upper roll is provided with a yoke 25 which is engaged by a spring 26 to press its surface against that of the lower roll to provide a 15 biting frictional grip between them. One end of this roll is provided with a short shaft 27 to the outer end of which is secured a knurled finger nut 28, the opposite end of this lower roll is drilled and a short split 20 shaft 29 is forced therein to provide a friction surface through which these feed rolls are driven by the movement of the plunger and this construction also permits this roll to be turned by means of the thumb nut 28 independently of the action of said plunger 25 for the purpose of setting the stamp strip relative to the cutters. This feature is of 30 particular advantage especially in affixing machines where rolls are employed for feeding the strip as in some cases it is found necessary to provide an adjustment for the strip in order to compensate for any creeping 35 during the feeding action, so that the strip will always be severed exactly midway between the abutting ends of the stamps.

In order to provide simple and effective means for rotating these rolls to feed the strip as the plunger advances, I have mounted 40 a pinion 30 on the friction shaft 29 whose teeth are adapted to engage those of the rack 20 and in order that this pinion should be operated during the stroke of the plunger in one direction only, I have removed some of 45 the teeth as at 31 therefrom, and on the end of the pinion I have provided a finger 32 positioned to project over the side thereof and arranged to be engaged by a pawl 33 pivoted at 34 on the rack, which pawl is 50 normally held in engaging position by the spring 35 against the stop pin 36, whereby when the plunger is in its up position this finger is in position to be engaged by the end of the pawl 33 to start the pinion rotating and bring its teeth into engagement with 55 those of the rack whereby a continued downward movement of the plunger rotates this pinion one complete revolution bringing the blank portion 31 of the pinion opposite the 60 toothed portion of the rack, by which construction the rack may be returned to its up position under action of the springs 57 without engaging or operating the pinion and its feeding rolls and as the pawl 33 passes the 65 finger 32 which now lies in a horizontal po-

sition it snaps over the finger ready to again engage it and start the pinion to rotating to bring its teeth into engagement with the rack as above described, when the plunger starts on its downward motion again, and 70 so this action is repeated as often and as rapidly as the plunger may be operated.

It will be noted that there are only sufficient teeth in the rack to rotate this pinion the required amount after which the plane 75 surface 58 of the rack serves as a positive stop to prevent further rotation of the pinion in the feeding direction.

In order to prevent a retrograde and backward action of the rolls or of the plunger, 80 providing the latter should be carried part way down, I have mounted a pawl 37 so that its end will engage the teeth of this pinion and permit it to rotate in one direction but positively prevent it from turning backward 85 and therefore this plunger is obliged after having once started to make a complete downward stroke to bring the blank portion 31 of the gear 30 opposite the rack before the plunger is permitted to return to normal. 90

In order to insure an accurate account being kept of the stamps issued I have mounted a counter 38 of usual construction in the frame of the machine and have connected the same through levers 39 and 40 so that the upper end 41 of lever 40 is engaged by the finger or pin 42 in the short shaft 27 whereby each complete feeding revolution of the rolls causes the counter to register, thus preserving an exact count of the number of stamps used from the machine. Each time the shaft 27 is rotated the pin or finger 42 engages the end 41 of the lever 40 and through the connection 49 operates the counter. 100

On the lower forward edge of the plunger head 19 I have mounted a foot 44 whose lower face is provided with a flexible pad 45 for pressing the severed stamp to the envelop. Also to this foot member is secured a spring knife blade 46, which may be formed in any suitable way but as an effective construction I have made the middle portion of the blade in the form of a spur 47 and the edges have been arranged on an upward slant from this spur toward the opposite edges of the blade, whereby a strip is first pierced by the spur and then cut in opposite direction toward the opposite edge of the blade. 110

A pair of downwardly projecting fingers 48 have been provided one at either edge of the blade which are arranged to engage the rounded edge 49 of the fixed cutter plate 50. This fixed cutter plate is provided with an 125 opening 51 through which the stamp is projected by the rolls just before the plate 46 descends to sever it.

The envelop is arranged to be moistened as it is passed along the table 52, by the 130

wick 53. This wick is held in the tube 54 and extends around to the rear of the casting where it is pivoted at 55, the opposite end of the wick extending into a suitable 5 reservoir portion 56 see Fig. 2 from which it receives its moisture by capillary attraction.

The operation of my improved stamp affixing machine may be more fully described 10 as follows:—

When the plunger is forced down the stamp rolls are rotated one complete revolution which draws outward the stamp strip from the roll 16 below, which advances one 15 length of stamp through the aperture 51 in the knife plate 50 to be severed by the descending of the spring blade 46, the severed stamp being carried down by a pad 45 against the moistened face of the envelop. 20 As the plunger is now released it is carried quickly upward by the action of the two spring fingers 57 ready to repeat the operation as often and as rapidly as desired.

By my improved construction no matter 25 how rapidly the plunger is forced downward the feed rolls are obliged to stop instantly when the plunger has finished its operating stroke and thereby effectually prevents any possibility of an over feeding of the stamp 30 strip.

My improved stamp affixing machine is very compact in its construction and very strong and durable.

Having thus described one illustrative embodiment of my invention I desire it to be understood that the specific terms employed are not for the purpose of limitation, the scope of the invention being defined by the appended claims.

40 I claim:

1. In a stamp affixer, an affixing plunger, positively driven rolls operated by the movement of said plunger for feeding a strip of stamps, a rack and pinion operated by the 45 movement of said plunger, and a pawl engaging said pinion for preventing retrograde movement of said plunger after rotation of the rolls has been started.

2. In a stamp affixer, an affixing plunger, 50 stamp strip feeding rolls, and means including a rack and mutilated pinion to positively operate said rolls to feed a stamp at each downward stroke of the plunger.

3. In a stamp affixer, an affixing plunger, 55 a pair of feeding rolls, means operated by said plunger for positively rotating said rolls to feed a strip of stamps, and friction means in connection with the rolls whereby the stamp strip may be adjusted relative to 60 the cutter.

4. In a stamp affixer, an affixing plunger, a pair of feeding rolls, means operated by 65 said plunger for positively rotating said

rolls to feed a strip of stamps, one of said rolls being provided with a recess, and a 65 shaft located within said recess and having means whereby said rolls may be adjusted to set the stamp strip.

5. In a stamp affixer, an affixing plunger, stamp strip feeding rolls, a rack carried by 70 the plunger, a mutilated gear on one of said rolls engaged by said rack, the mutilated portion of the gear being positioned to interrupt rotation of the rolls at the end of one revolution thereof, and to maintain the rack 75 and pinion in disengaged relation when the plunger rises, and means whereby the teeth of the mutilated gear may be again engaged with said rack.

6. In a stamp affixer, an affixing plunger, 80 stamp strip feeding rolls, a rack carried by the plunger, a mutilated gear on one of said rolls engaged by said rack, the mutilated portion of the gear being positioned to interrupt rotation of the rolls at the end of one 85 revolution thereof, and to maintain the rack and pinion in disengaged relation when the plunger rises, means whereby the teeth of the mutilated gear may be again engaged 90 with said rack, and a pawl engaging said pinion for preventing a backward rotation of said rolls by reverse movement of the plunger.

7. In a stamp affixer, an affixing plunger, stamp strip feeding rolls, a rack carried by 95 the plunger, a mutilated pinion on one of said rolls engaged by said rack, a pawl engaging member carried by said pinion and a pawl on said rack adapted to engage said member for positively causing the latter to 100 rotate and bring its teeth into engagement with the rack when the plunger starts to descend, and means for preventing a backward rotation of said rolls by any action of said plunger. 105

8. In a stamp affixer, an affixing plunger, stamp strip feeding rolls, said plunger being provided with a pair of spaced apart guide bars and a presser foot, one of said bars carrying a rack, and a pinion on one of said 110 rolls engaging said rack by means of which the rolls are actuated to feed the stamp strip.

9. In a stamp affixer, an affixing plunger, stamp strip feeding rolls, a gear on one of said rolls, a rack attached to said plunger 115 and engaging said gear, a stop on said gear, means carried by the rack to engage said stop to initiate rotation of the gear, and a counter-lever actuated by said stop.

In testimony whereof I affix my signature in presence of two witnesses.

WILLIAM H. GALE.
